UNITED STATES PATENT OFFICE.

PAUL DANCKWARDT, OF GALENA, SOUTH DAKOTA.

POWER-PRODUCING PROCESS.

1,023,819.

Specification of Letters Patent. Patented Apr. 23, 1912.

Application filed April 8, 1911. Serial No. 619,877.

To all whom it may concern:

Be it known that I, PAUL DANCKWARDT, a citizen of the United States, residing at Galena, county of Lawrence, and State of South Dakota, have invented certain new and useful Improvements in Power-Producing Processes; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to a power-producing process, and it may be considered an improvement on the process set forth in my previous Patent, No. 933,022, issued August 20, 1909.

The object of my present invention is to produce more power from a given amount of heat than is possible by following my previous process.

This invention involves a new principle, in so far as instead of one gas-forming fluid (as set forth in the aforesaid patent), which consists of a single substance of a particular boiling point, several gas-forming fluids of varying boiling points are used, these fluids being made up either of fractions of a mixture of several substances of different boiling points, as can be obtained by a fractional distillation, or they may be of different chemical composition, but must contain certain qualities, as hereinafter described. The process further differs from that set forth in my said patent, in so far as the circulating medium is heated in portions of the apparatus employed, to different temperatures, in order to render it possible to utilize the latent heat of the exhaust gases of the preceding portion or unit of the apparatus, for the generation of power in the following unit. It will be seen that with such a change in the process, a much larger percentage of the heat can be converted into useful power than in any other way.

The apparatus hereinafter described for carrying out my improved process, is a modification of that illustrated in my aforesaid patent for the practice of the process covered thereby.

It consists of a number of units as described in my previous patent, such changes, however, being embodied therein as have been found practicable and useful in such a combination.

The principal change in the apparatus consists in the fact that the condenser is placed on top of the apparatus, whereby I am enabled to perform the work without any pumps, as the condensed fluid can thus force its way back into the apparatus by means of its own gravity. The object of combining a number of units is to utilize the waste heat from one apparatus in the next one. The heat lost in my former apparatus is principally latent heat, and it is this which I intend to recover and utilize for the production of a greater amount of power in my improved process. I obtain this result by the use of a separate gas-forming fluid of a lower boiling point in each succeeding unit, so that the heat given up by the condensation of the next higher boiling fluid, is sufficient to volatilize the next lower boiling fluid. Any heat added besides this can, of course, generate still more gas.

Having briefly outlined my improved process, I will proceed to describe the same in detail, and in so doing will explain a suitable apparatus for carrying out or practicing the same, reference being made to the accompanying drawing in which is illustrated an embodiment thereof.

In this drawing: Figure 1 is a vertical section taken through an apparatus equipped for practicing my process where a single circulating fluid is employed. Fig. 2 is a horizontal section taken on the line 2—2, Fig. 1. Fig. 3 is a view illustrating a suitable apparatus for carrying out the process where different circulating fluids are employed in different units of the apparatus.

Referring now more particularly to Figs. 1 and 2, let the numerals 5, 6 and 7 designate three units which, except the condensers, are inclosed by a wall 8, preferably composed of brickwork. In the bottom of the chamber inclosed by this wall is placed a number of iron boxes 9 having lower compartments 10. From these compartments protrude pipes 12 which extend upwardly into larger pipes 13, whose upper extremi-

ties are secured in the bottom plates 14 of the iron top boxes 15. A larger pipe 16 connects the interior of each top box with motors 11 below, the motors being located 5 outside of the casing. Discharge pipes 17 communicating with the lower extremities of the pipes 16, pass outwardly through the wall of the chamber and communicate with the motors, a short return pipe 18 being employed to return the circulating medium to the iron box 9 of the unit. Condensers 19 are placed on top of the brickwork directly above the respective units 5, 6 and 7. Gas pipes 20 lead from the tops of the respective 10 boxes into the condensing chambers 19, while pipes 21 provided with valves 22, form conduits for the passage of condensed fluids from the condensing chambers into the lower compartments 10 of the bottom 15 boxes 9. By operating the valves 22 of pipes 21, all jointly, the machine can be shut down quickly. For this purpose the valves should be suitably connected to facilitate the operation. This detail is not illustrated, as nothing is claimed on the apparatus in this application.

On the extreme right-hand side of the apparatus, there is an extra condenserlike vessel 23, which serves as a cooler for a part 30 of the circulating fluid. This cooler has inlet and outlet pipes 24 and 25 for cold water. Through the cooler passes part of the circulating fluid, the latter entering the cooler by a pipe 26 communicating with a 35 pump 27 by means of which the fluid passes directly into the cooler through a pipe 28. The circulating medium leaves the cooler through a pipe 29 and passes first into the top 30 of the condenser farthest to the right. 40 After the circulating fluid enters the top chamber 30 of the condenser, it passes downwardly through the pipes 31, all of which communicate with a bottom chamber 32, whence this fluid passes through a pipe 33 45 to the bottom 32 of the next condenser, thence upwardly through the pipes 31 of the last named condenser, into the top chamber 30 of the same, thence through a top pipe 34 into the top chamber 30 of the condenser 50 farthest to the left, thence downwardly through the pipes 31 of the last named condenser into the bottom chamber 32, and thence downwardly from the said chamber to a pipe 35 into the chamber 36 of the iron 55 box 9 surrounding the pipes 12 and communicating with the pipes 13 heretofore described.

In case the circulating fluid consists of plain water, the cooler 23 can be dispensed 60 with, as in that case the cold water may be led directly into the last condenser, or that farthest to the right, and thence in succession toward the left through all of them and enter the bottom box of the first unit or that

farthest to the left. But as the cooler 23 would increase the amount of circulating fluid, there must be run to waste an equal amount of circulating fluid (plain water in this case), from the last unit. In order to complete the circle for the passage of part 70 of the circulating fluid, there have been provided pipes 37 connecting the large motor feed pipes 16 of each unit with the bottom box of the next following unit. All the units are separated one from another, by 75 partition walls 38 preferably formed of sheet metal, leaving openings 39 alternately near the top and bottom of the units for the heating medium, which enters the opening 40, to pass through. All the turbines or 80 motors 11 are mounted on the same shaft 41, supported in bearings 42. Pipes 43 provided with valves 44, serve for supplying the circulating medium and for regulating the level of it, while at suitable places (not 85 shown), water gages and thermometers may be provided for a more perfect control. Pipes 45 with valves 46 serve for filling said condensers with gas-forming fluid, and pipes 47 for withdrawing it from the bottom compartments 10 of the iron boxes 9, when desirable. The opening 40 in the wall 8 serves for introducing heat as heretofore explained. This heat may be from any desired source. The heated gases or products 95 of combustion are discharged through a pipe 48 communicating with the heating chamber at the upper right-hand corner, or a part of the chamber extremity remote from the opening 40 where the heat enters.

In order to operate the apparatus, I fill all the units with circulating fluid through pipes 43, to a suitable level. As a circulating fluid, any fluid not reacting chemically with the substances of the gas-forming fluid, 100 may be chosen. It may be, for instance, plain water, or better, a solution of a heavy substance in water or any other solvent, or an easily fusible metal or alloy, or any solid, fused at the working temperature, the 105 advantage of the latter ones consisting principally in their higher specific gravity, which allows the apparatus to be built on a much smaller scale in proportion to the same power. I further introduce into each 110 condenser, through pipes 45, a certain amount of gas-forming fluid. Each unit will receive a specific gas-forming fluid of a boiling point somewhat below the temperature of the circulating fluid contained 115 in that particular unit. To explain this better, let us suppose that I keep the circulating fluid in the different units at the following temperatures, beginning with the one on the left-hand as the first one: 95°, 120°, 89°, 83°, 77°, 71°, 65°, 59°, 53°, 47° and 41°; and presuming that I employ ten units altogether. Now I will select ten gas-form-

ing fluids that have boiling points which differ by about the same amount as the temperatures of the units. I will now presume that these gas-forming fluids have the following boiling points, respectively: 90°, 84°, 78°, 72°, 66°, 60°, 54°, 48°, 42° and 36°. The first of these compounds goes into the condenser of the first unit, the second one into that of the second unit, and so on. 10 Each unit will thus contain one circulating fluid kept at a temperature above that of the boiling point of the gas-forming fluid. These gas-forming fluids may be substances differing from each other chemically and 15 physically, or they may be made up partially or altogether by varying mixtures of the same compounds, but such mixtures must have the characteristic of the required difference in their boiling points, and they 20 must not react chemically with the circulating fluid.

The organic world offers a large number of suitable bodies, among which I will mention as cheap and practicable, the hydrocarbons, principally those contained in the coal oils, tar, oils, alcohols, ethers, ketones, carbon bi-sulfur, etc. Among the unorganic compounds, I will mention water, ammonia, mixtures of gases and water, or other solvents. Any substance or mixture of several, whether organic or unorganic, may be used as long as it has the desired boiling point, and does not react chemically with the circulating fluid.

35 Having supplied the apparatus with the fluids, I turn on the water to the cooler by opening valves of pipes 24 and 25. I then cause the heating medium which may be of any description, preferably waste heat, to 40 enter the opening 40. This will raise the temperature of all the units to the desired points. The gas-forming fluids will, upon the opening of the valves of pipes 21, enter by their own gravity, the lower compartments 45 of the bottom boxes, and coming into contact with the iron plates and pipes surrounded by the hotter circulating fluid, will be converted into gas, which forces its way up into the large pipes 13, lifting the 50 water contained therein into the upper boxes 15, from where it will fall into the downward pipes 16.

When starting the apparatus for the first time, the valves 46 of pipes 45 remain open, 55 until all the air contained in the apparatus has been expelled. As the left-hand pipes are now largely filled with gas, the pressure in the big pipes, being all filled with a heavy fluid, will force the turbines or motors 60 to revolve, while part of the circulating fluid will be forced to enter the neighboring box 9 of the second unit through the pipe 37, the pressure being there less than in the room above the turbine or motor. Thus a part of

the circulating fluid will pass from the hot-test unit through the whole row of units, imparting its heat to those units and thereby assisting them to keep up their temperatures to the points required for continuing the evaporating process, without receiving 65 much additional heat from the heating gases. If this were not the case the temperatures of these units would soon fall below the boiling points of the gas-forming fluids. That part of the circulating fluid which has 70 traveled thus from the first to the last unit leaves the latter one through the pipe 26, entering the pump 27 at a temperature somewhat above that of the boiling point of the respective gas-forming fluid, in my case 80 at about 41° centigrade. In passing through the cooler, its temperature is lowered to a point (about 30° in my case) at which it will be able to serve itself as a cooling fluid for the last condenser, for the gas- 85 forming fluid of the last unit was to have a boiling point of 36° centigrade. This will therefore condense by coming into contact with the walls of the condenser on the other side of which the 30° fluid is circulating. 90 By condensing, the gas gives off its latent heat to the circulating fluid, raising its temperature by several degrees, according to the quantity made to circulate through the row of condensers, in my case about 33° to 34°. 95 At this temperature the fluid enters the following condenser, where it undergoes a similar process of exchange of heat with the gas condensing there, and so on. In each condenser the temperature of the circulating 100 fluid is raised by picking up the latent heat of the condensing gases. When it leaves the condenser of the first unit it will have acquired, in my case, a temperature of about 87° centigrade; therefore has nearly recovered 105 all the heat it lost by passing through the units from left to right. Only a small amount of additional heat need to be added to make good the loss, while in the apparatus I first patented, all the latent heat was 110 lost, and I recommended therefore to use a gas-forming fluid of as small a latent heat as possible. In this modified process, the largest part of the latent heat is saved or utilized for producing power. To make this 115 advantage clearer, I will consider it somewhat in detail.

The average percentage of heat converted into power by gasifying a fluid and causing it to do work in a heat engine, is eight 120 per cent. when exhausting into a vacuum. This means that if I supply a certain amount of heat to the first unit, I get eight per cent. useful work out of the gas, and 92 per cent. will be lost in latent heat (no other losses considered here), of the gas formed. In my case, however, this gas is being condensed, surrenders this latent heat

to the condensing fluid, which returns it to the system. If I now suppose no other heat were available for producing power in the next following unit than this ninety-two 5 per cent. returned into the system, I could convert there in the second unit another eight per cent. of the ninety-two per cent. left saved, which is equal to 7.36 per cent. of the total heat, and in the following other 10 amounts, diminishing in the order: 6.77 per cent., 6.22 per cent., 5.73 per cent., 5.27 per cent., 4.85 per cent., 4.46 per cent., 4.10 per cent. and 3.78 per cent. The amounts saved in more than ten units would be so small as 15 to appear negligible for practical purposes, but in ten units I convert 56.5 per cent. of the total heat introduced into the system, into useful work. There are, however, still other advantages in placing several 20 units in series, one of which is the larger range of temperature between sources of heat and the last condenser, which is a leading item for the efficiency of any heat engine. The larger this the better, particu- 25 larly also for the reason that greater differences of temperatures between the units may be established, which secures a better condensation and allows the condensers to be built smaller. In this connection I will 30 mention expressly that there are better combinations of circulating fluids and gas-forming fluids than the above case presumes. A combination which affords a wide range of temperature between the 35 source of heat and last condenser, and consequently also between each two units, is that of a metal or an alloy as a circulating fluid in the first units, beginning with about 400° centigrade down to about 200° centi- 40 grade, from where the following units might contain a solution of a salt in glycerin as a circulating medium, and the last ones from 100° centigrade on downward a solution of a salt in water. Or the first 45 metal may be followed by mercury to the last unit. To obtain gas-forming fluids for such a wide range of temperature, the natural coal oil can be subjected to fractional distillation and suitable fractions cut out 50 and used for that purpose, or may be mixed with other substances, or other substances may be mixed in connection with them to fill out gaps, where their boiling points do not just suit. In the case here mentioned, in 55 which I make use of three different circulating media, it is obvious that the circulating fluid of the first unit cannot be allowed to pass any farther than the last unit containing the same circulating medium, and 60 the second one not beyond the last unit filled with that particular fluid. The pipe 37 therefore, connecting the last unit containing the metal or alloy with the first unit containing the glycerin solution, and

also the same pipe 37 connecting the last 65 glycerin unit with the first water unit, will have to be provided with a separate pump 49, which discharges the fluid through a pipe 50 into the condenser of the preceding unit, from where it passes on through the 70 others as in the former case, serving thus as the condensing medium for all but the last condenser of the set of units containing the same circulating medium. The condenser of the last unit of each set of units run on either metal or glycerin respectively, will receive as a condensing fluid that coming from the next following condenser as in the case before, but the fluid after having picked up the latent heat of the condensed 75 gas, is made to return into its own system or set of units by connecting a pipe 51 of each box with the bottom box 2 of the succeeding unit, at a point where a pipe 37 would otherwise enter. In this way it is 80 possible to transfer the waste (latent) heat of the preceding unit to the next following one, at the point where the two sets of units meet, and where the connecting pipes for the circulating fluid had to be removed, 85 through which the heat is transferred in the case of a single circulating fluid.

The feature of the process last described is illustrated in Fig. 3, in which two units only are shown, each unit, however, consisting of two members of the kind designated units in the form of construction shown in Figs. 1 and 2. Another feature of advantage of this improved process, is the low pressure at which the apparatus can 100 be run without suffering in efficiency. In the first case heretofore described, the pressure will be around one atmosphere absolute, which means that the pressure inside of the system equals nearly the outside pressure of the atmosphere. This circumstance 105 allows the apparatus to be built of cheap material and avoids dangers of leaks and explosions.

Having thus described my invention, what 110 I claim is:

1. A process of producing power which consists in heating several circulating fluids and several gas-forming fluids to different temperatures, the gas-forming fluids having 115 boiling points lower than the temperatures of the corresponding circulating fluids, causing the gases formed to react mechanically with the circulating fluids so that the latter will acquire velocity, utilizing the energy of 120 the circulating fluids for the production of power, and condensing the gases in order to repeat the operation.

2. The process of producing power, which consists in introducing gas-forming fluids 125 into several separate heated bodies of circulating fluid having varying temperatures, thereby imparting motion to the latter, the

gas-forming fluid introduced into each heated body of circulating fluid having a boiling point lower than the temperature of the said heated body of circulating fluid 5 into which it is introduced, condensing the exhaust gases, and utilizing the energy of the motive fluid for the production of power, substantially as described.

3. The process of producing power which 10 consists in heating portions of a circulating fluid below its boiling point, the temperature of the said portions gradually falling off, introducing into them portions of a mixture of other fluids, the boiling points of 15 which are lower than that of the corresponding portions of the circulating fluid, thereby creating gas, condensing the gas continually, and utilizing the gas pressure 20 for the production of power.

4. The process of producing power which 25 consists in heating circulating fluids and gas-forming fluids, the boiling points of the latter being lower than the temperatures to which the circulating fluids are heated, the 30 temperatures of each gradually falling off allowing the fluids to react calorifically and mechanically on each other, so that the circulating fluids acquire velocity, condensing the exhaust gases, and utilizing the energy of the moving fluids for the production of power.

5. The process of producing power which 35 consists in heating a circulating liquid and a gas-forming fluid, the boiling point of the latter being lower than that of the former, allowing them to react calorifically and mechanically on each other, so that the circulating fluid acquires velocity, causing fresh 40 amounts of gas-forming fluid of a lower boiling point than that of the first one to react calorifically and mechanically with fresh portions of circulating fluid, and a part of the old one, at a lower temperature than that of the first step, thereby creating 45 more gas, repeating this as often as gas can be generated by the remaining heat, condensing the exhaust gases, and utilizing the energy of the moving fluids for the production of power.

6. The process of producing power which 50 consists in bringing gas-forming fluids into contact with circulating fluids having temperatures higher than the boiling points of the corresponding gas-forming fluids, heating all in order to volatilize the gas-forming fluids, thereby imparting velocity to the circulating fluids, condensing the gases, and utilizing the energy of the moving fluids for the production of power.

7. The process of producing power which 60 consists in heating several bodies of circulating fluid to temperatures varying from each other and falling off gradually, bringing into contact with each one of them a

gas-forming fluid or a portion of a mixture 65 of gas-forming substances, the boiling point of each gas-forming fluid entering a certain circulating fluid, being below that of the temperature to which the respective circulating fluid is heated, thereby volatilizing 70 the gas-forming fluid and imparting velocity to the circulating fluid, condensing the exhaust gases, and utilizing the energy of the moving fluids for the production of power. 75

8. The process of producing power which 80 consists in heating circulating fluids or portions of one circulating fluid to temperatures gradually falling off, introducing into each one of them a particular gas-forming fluid or a portion of a mixture of gas-forming substances of a definite boiling point lower than the temperature to which the corresponding circulating fluid is heated, thereby 85 gasifying the former and imparting motion to the circulating fluid, allowing part of the circulating fluid of each higher temperature portion to flow over into the neighboring portion of lower temperature, thereby supplying the largest part of heat needed for 90 the further evaporation of the gas-forming fluids, causing a corresponding part of circulating fluid of lowest temperature to be cooled so that it may be used as a condensing fluid for the gases, returning it to the 95 first portion of the circulating fluid after having picked up all the latent heat of the gases, and utilizing the energy of the moving fluids for the production of power.

9. The process of producing power which 100 consists in heating circulating fluids to temperatures gradually falling off, introducing into each one of them gas-forming substance having definite boiling points lower than the temperature to which the circulating fluid is heated, thereby volatilizing the latter and imparting velocity to the circulating fluids, condensing the gases continually 105 and causing the latent heat of them to supply the largest part of the heat needed for 110 the continuance of the process, and utilizing the energy of the moving fluids for the production of power.

10. The process of producing power which 115 consists in heating portions of one circulating fluid to different temperatures, these falling off gradually, introducing into them the gases generated from other fluids of boiling points lower than the temperature of the corresponding portion of the circulating 120 fluid, thereby imparting velocity to the circulating fluids, condensing the exhaust gases in a way by which at the same time the latent heat of the gases is recovered, and utilizing the energy of the moving fluids 125 for the production of power.

11. The process of producing power which 130 consists in heating several circulating fluids

to different temperatures, these falling off gradually, introducing into them the gases generated from other fluids of lower boiling points than the temperatures of the corresponding circulating fluids, thereby imparting velocity to the circulating fluids, condensing the exhaust gases in a way by which at the same time the latent heat of the gases

is recovered, and utilizing the energy of the moving fluids for the production of power. 10

In testimony whereof I affix my signature in presence of two witnesses.
